UNITED STATES PATENT OFFICE.

OSCAR L. LOUGHEAD, OF RACINE, WISCONSIN.

VACUUM FEED DEVICE.

Application filed March 13, 1922. Serial No. 543,238.

My invention relates to vacuum feed devices, and more particularly that type of vacuum feed device adapted to supply fuel from a low level supply tank to the carburetor of an internal combustion engine. I contemplate a compact fuel feed device which may be made substantially a unit with the carburetor, being made either as an entirely separate device to be attached adjacent the inlet to the float chamber of a carburetor of substantially any design or to be attached to the float chamber of a carburetor as a substitute for a part of the float chamber or to be made integrally with the float chamber of the carburetor.

I also contemplate a feed device of such novel construction and design that the various parts may be quickly and easily assembled and disassembled without disturbing any adjustment, the float, the snap-over mechanism and its support forming a unit which may be removed as a whole, while the majority of the ports entering the chambers of the device and the coupling means specified are mounted on one piece which likewise may be removed as a unit.

Among other objects are the use of but one adjustment for regulating both the suction and atmosphere valves, the provision of a design such that sheet metal stampings may effectively be used for the walls of the chambers, and also means for attaching the device directly to the float chamber of a carburetor having its inlet valve at its bottom, the attachment being of such novel character that the attaching means may be used as a fuel conduit to the float chamber.

Referring to the drawings:

Figure 1 is an elevation of a vacuum feed device embodying the principles of my invention, the device being mounted upon the inlet of a carburetor;

Figure 2 is a vertical longitudinal section of the device taken in the plane of Figure 1;

Figure 3 is a plan view of the device with the upper or suction chamber removed together with the upper central supporting post;

Figure 4 is a plan section taken on the line 4-4 of Figure 2 and showing the snap-over mechanism;

Figure 5 is a vertical detail section of the snap-over mechanism taken on the line 5-5 of Figure 4;

Figure 6 is a vertical longitudinal section of the device as attached directly over and replacing the usual cover of a carburetor float chamber;

Figure 7 is a view partly in longitudinal vertical section of the device made integrally with the carburetor float chamber; and

Figure 8 is a bottom section taken on the line 8-8 of Figure 7, the float mechanism of the carburetor float chamber being omitted.

Referring for the present to Figures 1 to 5, inclusive, I show the device as a complete unit 10, which may be threaded by a nipple at its base into the elbow 11 or other fitting communicating with the inlet of a float chamber 12 of a carburetor 13.

The device comprises a suction chamber 14 enclosed by an inverted cup or bowl 15, preferably stamped from sheet metal, and a supply chamber 16 enclosed by a lower cap or bowl 17, similarly stamped from sheet metal. Interposed between the bowls 15 and 17 is a plate 18 which constitutes respectively the bottom and top of the suction chamber 14 and the supply chamber 16. Into the upper surface of plate 18 and communicating with a radially drilled suction port 19 is a hollow plug 20, the upper edge of which constitutes a valve seat 21. A hollow supporting post 22 is threaded onto the plug 20 and extends upwardly through an aperture in the top of the bowl stamping 15 where it is engaged by hollow cap nut 23 which serves to clamp the bowl 15 against the plate 18 forming a fluid tight joint therebetween.

Threaded into the upper end of the supporting post 22 is a short sleeve 24 into which in turn is threaded a hollow screw 25, the lower edge of which forms an adjustable valve seat 26. A lock nut 27 serves to secure the vertical adjustment of the valve seat 26 and also to insure an air tight connection between the screw 25 and the sleeve 24. Within the reduced bore of the supporting post 22 is reciprocably mounted a valve stem 28 provided at its lower end with a tapering point adapted to co-operate with the valve seat 21.

to control the admission of suction through the suction port 19 to which suction is led by any suitable means such as a conduit 29 communicating with the intake manifold 30 of the engine. A loosely fitting conical cap 31 is provided at the upper and reduced end of the valve stem 28, the cap joint 31 being provided with a bore sufficiently large to allow a limited universal movement of the cap relative to the valve stem 28, whereby the former will always center itself correctly in the valve seat 26. Below the cap 31 the valve stem 28 is provided with a pair of spaced flanges 32 between which lies the bifurcated end of a valve actuating lever 33 which is pivoted at 34 to a pair of ears 35—35 struck from or formed on the post 22. The outer end of the lever 33 carries a horizontal transverse rod 36 at the ends of which are secured the ends of a pair 20 of tension springs 37.

A substantially U-shaped supporting bracket 38 is supported upon the ears 35 of the post 22 by means of portions 39 of the legs of the U bracket which are bent back 25 upon themselves in spaced relation. A pair of studs 40 project inwardly from the web 41 of the U bracket 38. A U-shaped lever 42, preferably formed of strap metal similar to that used in the U bracket 38, is mounted 30 with its web 43 lying on the inner surface of the web 41, being pivotally supported in that position by the studs 40 which project through suitable apertures in the web 43. At their free ends, the legs of the U lever 42 are secured to the opposite ends of the said 35 tension springs 37. Depending lugs 44 are formed from the legs of the U lever 42 and to these lugs are pivotally secured small angle brackets 45, which are secured to the upper 40 surface of a float 46. The float is provided with a central opening 47, whereby the float is vertically reciprocable along the post 22.

As shown in Figures 2, 4 and 5, the free ends of the U lever 42 are above a dead center relation between the pivot 34 of the valve actuating lever 33 and the outer end of the latter, whereby the inner end of the valve actuating lever contacts the lower flange 32 of the valve stem 28, causing the lower end 50 of the stem to co-act with the seat 21 to prevent the admission of suction through the bore 19. It will be noted that in this position the valve cap 31 is away from its seat 26 allowing atmospheric pressure to enter the suction chamber 14 through the hollow screw 25 and the apertures 23' in the cap nut 23. The admission of atmosphere to the suction chamber 14 allows the fuel to pass through a check valve 48 supported on the 55 plate 18 into the supply chamber 16.

As the float 46 lowers, due to the fall in the fuel level, the U lever 42 will be swung downwardly about the studs 40 due to the pivotal connection between the lugs 44 and 60 the brackets 45 of the float until the ends of

the tension springs which are carried by the U lever 42 pass below a dead center relation with the pivot 34 of the valve controlling lever 33 and its pivotal connection with the opposite ends of the springs, at which time 70 the levers 33 will be caused to snap over in a well-known manner, raising the valve stem 28 to its alternate position in which the pointed cap 31 will seat against the valve seat 26, closing the suction chamber 14 to 75 atmosphere and admitting suction thereto through the now open valve seat 21. The valve stem 28 is obviously loosely fitting in the post 22 and accordingly when it is unseated from the seat 21 the suction through 80 the radial bore 19 is at once effective in the suction chamber 14.

The suction thus created in the chamber 14 serves to draw fuel thereto through the supply conduit 49 and elbow fitting 50 and 85 the ports 51 in the plate 18. The elbow 50, it will be noted, is provided with an outward flow resisting ball check valve 52 which is provided with a light expansion spring 53 designed to hold the valve closed against 90 only very low pressure, the purpose of this being to prevent the flooding of the float chamber when the fuel supply tank is higher than the vacuum feed device, such as might occur with an automobile on a steep hill. I 95 prefer to so construct this valve that the ball 52 will not completely prevent back flow, but will allow fuel in chamber 14 to drain back into the fuel supply tank after standing a few hours. The check valve 48, previously 100 referred to, which is supported in the plate 18 and communicates between the float chamber 14 and the supply chamber 16, is in the form of an elbow, the lower and horizontal portion of which is provided with a ball 54 105 and a valve seat 55 so positioned that the center of the valve seat is somewhat above the center of the ball as it normally rests in its inoperative position. When suction is admitted to the suction chamber, the ball 54 will 110 be drawn to the valve seat 55 and lifted slightly to seat thereagainst, but when the suction in the suction chamber is destroyed, the ball 54 will drop by gravity, unseating itself from the valve seat 55. In this way it 115 is insured that the check valve 48 will at all times be open except when suction is admitted to the suction chamber 14, there being no opportunity for corrosion or adhesion of the ball against the valve seat.

A lower post 56 is threaded into the plate 18 and depends therefrom, a reduced portion of the post passing through an aperture in the bottom of the lower bowl stamping 17 and provided with a nut 57, whereby the bowl 12 17 is clamped tightly against the lower surface of the plate 18 and also against a shoulder 58 on the post 56 to form a fluid tight joint therebetween. At its lower end, the post 56 is provided with a longitudinal bore 13

59 which communicates with cross bores 60 which are spaced above the bottom of the chamber 16 to form a drain trap for sediment and water which may be withdrawn through 5 the drain cock 61. Atmosphere is introduced to the chamber 16 through a tube 62 supported in and passing through the plate 18 and extending upwardly through an air tight joint in a hollow screw 63 at the top 10 of the suction chamber 14.

As shown in Figure 1, and as previously explained, the entire device 10 is threaded by means of the protruding nipple end of the post 56 into the elbow 11 communicating 15 with the inlet of the carburetor float chamber 12. To remove the device entirely, it is necessary only to uncouple the suction conduit 29 and the fuel feed conduit 49 and unscrew the device from the elbow 11. However, if it is desired merely to adjust or inspect the snap-over mechanism, the cap nut 23 is unscrewed, allowing the inverted bowl stamping 15 to be withdrawn, after which the supporting post and its associated plug 25 may be unscrewed from the plate 18. It is also to be noted that for making adjustments of the valves, it is necessary merely to remove the cap nut 23 when the hollow screw 25 and the lock nut 27 may be manipulated.

30 In Figure 6 I have illustrated the device of my invention as applied in a novel manner to the float chamber 70 of a carburetor 71, there being no alterations required in either the float chamber or the carburetor. 35 The usual cover of the float chamber which supports the valve controlling mechanism is replaced by a supply chamber casing 72 of the supply chamber 73, which bears on its bottom the valve controlling mechanism 70' of the cover. The top of the supply chamber 73 is closed by a plate 74 (similar to plate 18 of Figure 2) which is held against the casing 72 by a plurality of screws 75. The plate 74 also constitutes the bottom of a suction chamber 76, the walls of which I have shown as being formed by a glass cylinder 77 and a cover 78. A pair of hollow tubes 78' are secured to the plate 74 and extend upwardly through the cover 78 where they are provided with nuts 79 whereby the cover 78, the glass cylinder 77 and the plate 74 are all clamped together in air tight relation. The tubes 78' also form a passage communicating between the nuts 79 and the supply chamber 73 where- 45 by the latter is continuously relieved to atmosphere.

The several parts of the suction chamber 76 are also clamped together by the nut 23 and the supporting post 22, which, together 50 with the snap-over mechanism and float, are similar to the corresponding parts shown in Figures 1 to 5, except that the float 46 is provided with longitudinal grooves, as shown at 55 80, to provide space for the tubes 78'. The plate 74, similarly to the plate 18, is provided

with inlet ports to the suction conduit 29 and the fuel conduit 49. The carburetor float chamber 70 is provided with a float controlled inlet valve 81 adjacent its bottom which seats against the upper end of a hollow plug 82. 70 The usual intake fitting about the bottom of the float chamber has been supplanted by a fitting 83 secured thereto by a plug 84, the fitting comprising a hollow hub 85 and a pair of outwardly and upwardly extending hollow 75 arms 86. A pair of hollow vertical tubes 87 lie outside of the float chamber 70 and extend between bosses 88 at the lower edges of the casing 72 and the ends of the hollow arms 86 of the fitting 83, the casing 72 being clamped 80 against the top of the float chamber by cap nuts 89 at the lower ends of the tubes 87. It will be noted that a continuous passage is afforded between the supply chamber 73 and the valve seat 82 of the float chamber by means 85 of the tubes 87, the arms 86, the passages 90 in the plug 84 and the hollow plug 82. A suitable vent to atmosphere is provided adjacent the top of the float chamber 70, such as by a small duct 91.

90 It is thus to be observed that I have provided a construction whereby a vacuum feed device embodying the principles illustrated in Figures 1 to 5 may be easily and rigidly secured to the float chamber of a standard carburetor without the necessity of removing the carburetor from the motor or of making any material alterations in the carburetor or its float chamber.

95 In Figures 7 and 8 I have shown the device 100 as an integral part of the float chamber of a carburetor, using a construction which embodies the principles of the device hereinbefore described. The float chamber 70 is provided with an integral jacket 95 concentric therewith and forming an annular supply 105 chamber 96 around the sides and bottom thereof. The float chamber 70 and the jacket 95 are here shown as an integral casting, the two parts being tied together by a plurality of 110 webs 95' adjacent their upper edges and at their bottoms by a post 97 in which are threaded the valve seat bearing hollow plug 82 and a drain plug 98. The upper edges of 115 the float chamber 70 and the jacket 95 terminate in the same horizontal plane and are covered by a plate 99 secured thereto by means of screws 100. The plate 99 is very similar to the plate 74 previously described, and, like the latter, constitutes the bottom of the suction chamber 76 and supports the post 22 which carries the float snap-over mechanism. One of the tubes 78 communicates directly 120 with the float chamber 70, relieving it to atmosphere, while the other tube communicates through a cross bore 101 in plate 99 with the supply chamber 96, whereby the latter is also constantly relieved to atmosphere. The check valve 48' between the suction 125 chamber 76 and the supply chamber 96 is here 130

shown as being somewhat smaller than the check valve in Figure 6 in order that it may project downwardly into the supply chamber 96 between the jacket 95 and the float chamber 50. The check valve 48 communicates with the suction chamber 76 through a cross bore 102 in the plate 99. The plate 99, similarly to the plate 74 of Figure 6, comprises an inlet port 51 for the fuel conduit 49 and the 10 suction port 19 for the suction conduit 29.

It will be seen from Figures 7 and 8 that without greatly increasing the size of the carbureter, the device of my invention can be embodied integrally therewith with great 15 compactness, sturdiness and economy.

While I have shown only specific embodiments of certain types of vacuum feed devices embodying the principles of my invention, I do not wish to be limited thereby further than 20 by the scope of the appended claims.

What I claim is:

1. A vacuum feed device comprising a suction chamber, a fuel inlet communicating therewith, an outlet therefrom including an 25 inward flow resisting check valve, a post extending vertically through said suction chamber, aligned suction and atmosphere valves for creating and destroying suction in said suction chamber, a fuel level actuated snap- 30 over mechanism for reciprocating said valves comprising a lever pivoted on said post, one end of said lever engaging said valve and the other end secured to one end of a tension spring, a second lever pivotally supported 35 from said post and secured to the opposite end of said spring, and a float lying about said post and reciprocable thereon, said second lever being pivotally connected to said float whereby reciprocation of said float by 40 the rise and fall of fuel in said suction chamber causes the second-mentioned end of said spring to move past a dead center relation with said first-mentioned lever.

2. A vacuum feed device comprising in 45 combination a carbureter float chamber, a jacket lying about said float chamber and constituting a supply chamber, a float control valve for admitting fuel from said supply chamber to said float chamber, a suction 50 chamber above said float chamber, a plate covering the tops of said float and supply chambers, said plate constituting the bottom of said suction chamber, a suction conduit communicating with said suction chamber 55 through said plate, a valve in said suction conduit, an air valve for relieving said suction chamber to atmospheric pressure, float actuated valve controlling means in said suction chamber for actuating said suction valve 60 and said air valve whereby suction and atmosphere are alternately admitted to said suction chamber, a check valve supported from said plate and communicating between said suction chamber and said supply chamber, said check valve being normally opened 65

by gravity and being closed by the suction in said suction chamber, and means for admitting atmospheric pressure to said float chamber and said supply chamber.

3. A fuel feed device comprising a suction chamber, a fuel inlet thereto and outlet therefrom having a check valve, valve means for intermittently and alternately admitting suction and atmosphere to said chamber, and valve actuating means comprising a float in 70 said chamber, a stationary support carrying a fixed U shaped bracket, a U-shaped lever pivotally supported at its web to the web of said U bracket, a valve actuating lever for actuating said valve means, a pair of tension 75 springs between the ends of the legs of said U lever and said valve actuating lever, said U lever being moved about its pivot by said float to which it is pivotally connected whereby the admission of suction is governed by 80 the fuel level in said chamber.

4. A suction fuel feed device comprising a receptacle forming a closed chamber having a base provided with a suction inlet, a hollow post extending through the chamber and secured at its lower end to said base and extending at its upper end without said chamber, a suction port carried by the lower end of the post in communication with said suction inlet, an atmospheric port carried by the upper end of the post and communicating with atmosphere, a valve member reciprocable within the post for alternately opening and closing the respective ports, and a float mechanism in the chamber for controlling the 90 valve, the post together with the suction and atmosphere ports which it carries and the reciprocable valve being separable as a unit from the receptacle and base whereby the adjustment of the valves may be made before 95 the unit is positioned in the receptacle.

5. In a suction fuel feed device, the combination of a receptacle having a base, side walls and a top, a hollow post secured to the base and extending through the chamber and the top, a suction inlet port at the lower end of said post, an adjustable atmospheric port at the upper end thereof, a valve member reciprocable between the two ports to close them alternately thereby successively admitting suction and atmosphere to the suction chamber, float mechanism in the chamber for controlling the valve, and a nut threaded on the upper end of the post for clamping the top of the receptacle to the base and removable independently of the setting of the atmospheric port.

6. A fuel feed device comprising a suction chamber, a fuel inlet thereto and outlet therefrom having a choke valve, valve means for intermittently and alternately admitting suction and atmosphere to said chamber and valve actuating means comprising a float in 100 said chamber, a stationary support for the float carrying a fixed laterally extending 105

bracket, a lever pivotally supported at its outer end to the outer end of said bracket, a valve actuating lever for actuating said valve means mounted upon said support, a tension spring connecting the inner end of said first named lever and the outer end of said valve actuating lever, said first named lever being moved about its pivot by said float and having pivotal connection with the float whereby the admission of suction is governed by the ¹⁹ fuel level in said chamber.

In witness whereof, I hereunto subscribe my name this 8th day of March, 1922.

OSCAR L. LOUGHEAD.
